UNITED STATES PATENT OFFICE.

HARRISON L. STALEY, OF HARTFORD, CONNECTICUT.

ATOMIZER OIL BURNER.

Application filed March 17, 1924. Serial No. 699,884.

This invention has relation to that type of oil burner in which the oil is atomized by and commingled with steam prior to injection into the combustion chamber, and the 5 special object of this invention is to so construct the atomizing device that steam will be used at boiler pressure at the atomizer nozzle, thereby insuring a more minute subdivision of the oil and a more thorough commingling of the atomized oil and steam, as 10 more specifically hereinafter set forth.

In the drawing—

Fig. 1 is a longitudinal sectional view of one form of my device;

15 Fig. 2 is a similar view of another form of my device.

Referring to the form of device shown in Fig. 1, 5 designates a mixing chamber, through the side wall of which enters the oil-conduit 6, the inner end of this conduit being turned at right-angles so as to deliver the oil in an outward direction so as to form an outwardly-directed nozzle, the interior of the end of the nozzle being bevelled to form 20 a seat for the bevelled end of a valve-pin 7. This valve-pin is slidably mounted in a tube 8 and its outer end 9 is threaded into a bracket 10 for adjustment purposes, a hand-wheel 11, preferably graduated, being 25 affixed to the valve-pin for conveniently rotating it in adjusting it toward and from the nozzle to regulate the quantity of oil delivered into the mixing-chamber.

30 Steam enters the mixing-chamber at the opposite side from the oil-inlet 6 by means of a conduit 12, the inner end of this conduit terminating in a cylinder 13 which surrounds the oil-nozzle and is concentric therewith, the cylinder being sufficiently larger than the cylindrical nozzle to form an annular space therearound. The nozzle pipe 6 extends through the wall of the cylinder near the inner end thereof, which inner end is desirably closed by a hemispherical wall 45 14. The outer end of the cylinder 13 is open and terminates within the mixing-chamber. The forward end of the mixing-chamber is closed by a screw-cap 15, into which the inner end of the aforesaid tube 8 is threaded, the inner end of said tube 8 terminating within the mixing-chamber. The cap 15 is provided with a cylindrical cavity 16 in alignment with the cylinder 13, and

slidably mounted in the cylinder 13 is an atomizer-throttle-valve 17 of cylindrical form, this valve extending across the space between the outer end of the cylinder 13 and the cap 15, so that its outer end will slidably work in the cylindrical cavity 16 in the cap. 55 60

The cylindrical valve 17 abuts the inner end of the tube 8 and its outer end is provided with a hole through which the inner end of the valve-pin 7 slides. The valve 17 can therefore be adjusted back and forth by 65 screwing the tube 8 in or out, a thumb-wheel 18 being provided for conveniently turning said tube 8, and suitable stuffing-boxes 19 and 20 being provided to prevent the escape of steam. It will be observed that the oil-valve 7 and the steam-valve 17 may be adjusted independently. 70

75 The steam-valve 17 is in the form of a hollow cylinder whose outer end is closed except that, as stated, a central hole is provided for the passage of the oil-valve 7. The cylinder is hollow and surrounds the oil-nozzle, the inner end of the cylinder being open to the steam-chamber. About midway the length of the cylinder valve 17 it 80 is provided with an interior annular rib 21 which is bevelled on its inner face so as to cooperate with a bevelled valve-seat on the outer side of the oil-nozzle, so that by forcing the valve cylinder inwardly, the bevelled 85 face of the rib 21 closes against the bevelled outer valve-seat on the nozzle and thus throttles the steam. The valve cylinder 17, at a point between the valve-rib 21 and the outer closed end of the valve cylinder is provided with an annular port 22 which communicates all around with the annular mixing-chamber, the adjacent part of the wall of the cap 15 being concaved at 23 for the purpose of assisting in reversing the atomized oil and steam and throwing the same 90 95 back into the mixing-chamber. The annular port 22 in the valve cylinder is crossed at intervals by spider members 24 which serve merely as a means of connecting the head 100 of the cylinder to the inner part of the cylinder.

105 It will be observed that in the construction described, an annular stream of steam is maintained around the oil-nozzle and that the atomized oil will be projected annularly

outwardly into the outer end of the mixing-chamber, where the curved portions 23 of the end wall of the mixing-chamber will turn the stream of oil and steam back upon itself into the mixing-chamber, thereby causing the particles of oil and steam to swirl and thus become intimately mixed before exit at the mixture-discharge-opening 25, which, as usual, leads to the combustion chamber. The oil is discharged from the nozzle 6 in the form of an annular film and the steam is discharged in a similar form surrounding the annular body of oil, and the bevelled faces of the parts which form the steam nozzle are so arranged that the annular body of steam is directed across the issuing film of oil, thereby insuring an immediate comminuting of the oil. It will be observed that the annular port 22 of the valve cylinder has its walls curved so as to properly direct the commingled oil and steam against the end wall of the mixing-chamber all around the same, thereby providing a practically unobstructed passage-way into the mixing-chamber, the obstructions offered by the two or three spider members 24 being negligible. The pressure of the steam normally holds the valve cylinder against the inner end of the abutment 30 adjusting-tube 8.

It will therefore be observed that the atomizer valve 17 forms also the throttle-valve of the steam supply, or, in other words, the steam throttle is so positioned and constructed that it performs the additional function of an atomizer. In this class of burners as heretofore constructed, the steam has always been throttled at a point distant from the atomizer, so that the steam 40 at the atomizing point was always below boiler pressure. In my construction, it will be observed that no matter how fine I throttle down the steam, it is still at boiler pressure, whereby the atomization of the oil to 45 a very thorough extent is insured in every adjustment of the steam atomizer valve. Thus bringing boiler pressure to the atomizing point has the further advantage that the aspirating function is greatly increased 50 as compared with the burners now generally used, whereby I am able to greatly reduce or entirely do away with the need for supplying the oil under pressure.

In the construction shown in Fig. 2, I 55 have swivelled the atomizing valve to tube 8 so that the valve may be moved positively back and forth. I have also set back the atomizing nozzle members from the point of exit of the oil, the bevelled valve-seat on 60 the nozzle tube being formed on the outer face of the annular rib 26 on the nozzle tube 6. I also show a tubular extension 27 on the inner end of the oil valve rod 7, this tubular extension being adapted to slide back 65 and forth in the nozzle tube 6, to thereby

insure a steady support for the inner end of the valve stem 7. The tubular extension 27 is provided with an annular series of openings 28 for the admission of the oil directly into the annular stream of steam coming 70 from the steam nozzle. The cap 15 is not screwed to the mixing-chamber, as in Fig. 1, but is clamped thereto by a ring 29. By removing the cap 15 in either construction, it will be observed that I get access to all 75 the working parts, whereby I am enabled to clean and repair the interior parts very readily and without dismantling the whole structure. It will be observed also that by graduating the thumb-wheels 11 and 18, I 80 facilitate the proper operation of the device, since after I get the desired character of flame, by the trial method, with a certain pressure of steam and oil, I can, by noting the positions of the wheels on the scales, get 85 that same adjustment again without difficulty.

What I claim as new is:

1. An atomizing apparatus for oil burners embodying a mixing-chamber closed at its outer end and having an exit for the mixture at its other end, an oil-nozzle and an adjustable valve therefor, a steam-supply conduit leading to the oil-nozzle, and a steam nozzle having an adjustable steam 90 throttle-valve adjacent the oil-nozzle constructed to atomize and aspirate the oil at said nozzle, said nozzles being located within the mixing-chamber and arranged to direct the mixture toward said closed outer 100 end of the mixing-chamber so that the mixture must reverse before making its exit to the combustion-chamber.

2. An atomizing apparatus for oil burners embodying a mixing chamber closed at its outer end and having an exit for the mixture at its other end, an oil-nozzle and an adjustable valve therefor, a steam-supply conduit leading to the oil-nozzle, and an adjustable steam throttle-valve adjacent the oil-nozzle constructed to atomize and aspirate the oil at said nozzle, said oil-nozzle entering the mixing-chamber and extending outwardly away from said exit, said steam-supply conduit entering the mixing-chamber and therein formed into a cylinder surrounding the nozzle and having its outer end open, said throttle-valve being slidably mounted in said cylinder.

3. In an oil-burner of the type set forth, 120 a mixing-chamber having a closed outer end and an open inner end for delivering the mixture to the combustion-chamber, an oil-nozzle enclosed within the mixing-chamber and directed toward said closed end, a steam-nozzle surrounding the oil-nozzle and likewise enclosed within said mixing-chamber and directed toward said closed end, a steam-valve surrounding the oil-nozzle and having an annular lateral discharge port for 125 130

delivering the mixture into the outer end of the mixing-chamber, a tubular valve-stem threaded through an opening in the forward end of the mixing-chamber for operating the steam-valve, an oil-valve slidably extended through said tubular stem and into the steam-valve, and a bracket having a

threaded connection with the outer end of said oil-valve to permit the same to be adjusted independently of the steam-valve. 10

In testimony whereof I hereunto affix my signature.

HARRISON L. STALEY.
